Attorney.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING-MACHINE.

1,389,949.

Specification of Letters Patent.

Patented Sept. 6, 1921.

Application filed October 1, 1919. Serial No. 327,732.

To all whom it may concern:

Be it known that I, ALFRED G. F. KUROWSKI, a citizen of the United States, formerly a citizen of Germany, residing in Brooklyn 5 borough, in the county of Kings, city and State of New York, have invented certain new and useful Improvements in Typewriting-Machines, of which the following is a specification.

10 This invention relates to typewriting machines, and is herein disclosed as applied to an Underwood standard typewriting machine carriage, which is modified to enable special kinds of work to be done. As here- 15 in illustrated, the typewriting machine carriage comprises a platen, which is adapted to be moved away from the feed-rolls to enable a thick pack of work-sheets and carbon-sheets to be inserted around the platen; and 20 also as comprising a card-holder which is normally disconnected from the platen, but which is adapted to be connected thereto.

The present invention provides means whereby, when one set of devices is set for 25 one kind of work, the other set of devices may be held ineffective and locked against movement.

According to the present disclosure of the invention, such means may include one handle or finger-piece for moving the platen and another handle or finger-piece for connecting the card-holder to the platen. Hooks may be provided for locking said finger-pieces, said hooks being so connected that 35 one or the other is always effective.

Other features and advantages will hereinafter appear.

In the accompanying drawings,

Figure 1 is a perspective view of an Underwood standard typewriting machine as 40 modified to include one form of the present invention.

Fig. 2 is a detail rear view, showing the platen disconnected from the card-holder.

45 Fig. 3 is a diagrammatic side view, in section, showing neither finger-piece actuated, that is, with the machine adapted to do ordinary typewriting.

50 Fig. 4 is a similar view, showing the platen withdrawn to permit the insertion of a thick pack of work-sheets and carbon-sheets.

Fig. 5 is a detail rear view, showing the position of the rack when the finger-piece is

actuated to connect the card-holder to the platen.

Fig. 6 is a view similar to Fig. 3, but showing the finger-piece actuated to connect the card-holder to the platen, as in Fig. 5.

The typewriting machine carriage comprises a rear paper-table 10 behind the platen 11, so that work-sheets passed down over the paper-table 10 pass beneath the platen 11 and engage the feed-rolls 12 and 13, so that they are guided upwardly to the front of the platen to permit the types 14 to print upon them at the printing line.

The platen is journaled in a frame which comprises ends 15 and 16 and includes the paper-table 10, the frame forming part of the carriage 17, upon which is mounted the line-space lever 18, which is adapted to rotate the usual line-space wheel 19, by driving the usual line-space slide 20.

When it is desired to insert a thick pack of work-sheets and carbon-sheets over the 75 paper-table 10, around the platen, a handle or finger-piece 21, pivoted at 22 upon the platen-frame end 15, may be drawn forward so that an extension 23 of the handle will carry a lug 24 thereon beneath a rock-arm 25, fast upon a shaft 26 journaled in the ends 15 and 16, with the result that the platen 11 will be drawn upwardly and rearwardly by the upswinging of the rock-arm 25. The connections for accomplishing this include a 80 rock-arm 25 at each end of the frame, each rock-arm connected to a link 27, which is pivoted at its forward end 28 to the free end of a swinging arm 29, pivoted at 30 in the adjacent end 15 or 16. The arms 29 are pro- 90 vided with openings forming journals for the ends of the platen-axle 31, with the result that, as the rock-arm 25 rises, the links 27, in drawing the arm, draw the platen rearwardly by its axle, the axle riding in slots 32 in the end-plates 15 and 16. Said slots are adapted to guide the platen upwardly and rearwardly away from the feed-rolls 12 and 13, to permit the thick pack of work-sheets and carbon-sheets to be inserted be- 95 tween them. Normally the shaft 26 holds the platen in its forward position with the axle 31 at the forward ends of the slots 32. To effect this, the shaft 26 is provided with strong torsion springs 33, coiled around it 100 and normally holding a pin 34 upon the

rock-arm 25 in a depression 35 in the extension 23 of the finger-piece 21, with the result that the links 27 and the rock-arms 25 stand just below dead center, thus holding the 5 platen firmly in position.

In order to arrest the finger-piece at the proper position to hold the rock-arms 25, there is provided a lug 36 upon the end 15, adapted to be struck by a bend 37 in the finger-piece 21. Thus, when the parts occupy 10 the Fig. 2 position, the platen is in its normal writing position.

To enable writing to be done upon cards, the machine is herein illustrated as comprising 15 a channel-bar 38, normally lying below and under the front of the platen, and having clips 39 adapted to hold a card inserted in it. The channel-bar 38 is adapted to be connected to the platen by racks 40, of which 20 there is one pivoted to each end of the bar, each rack adapted to mesh with a crown gear 41, fast to the adjacent end of the platen, but normally standing clear of its gear. When it is desired to write upon a 25 card, the channel-bar 38 may be raised by first connecting it to the platen and then advancing it through the platen by the line-space lever 18 or hand-wheel 42. To connect the channel-bar 38 to the platen, a finger- 30 piece 43, journaled at 43^a on the frame end 16, may be drawn forward so that a rock-arm 44 fast to a stub-shaft 45, also fast to the handle 43, swings downwardly at the actuation of the handle, with the result that 35 a link 46, pivoted to the rock-arm 44 and also pivoted to a rock-arm 47 fast upon a rock-shaft 48, causes the racks 40 to mesh with the gears 41.

The connections between the shaft 48 and 40 the racks 40 include bent-over rock-arms 49 fast upon the shaft, and having their bent-over ends pivoted to links 50, with the result that, when a link 50 drops, it rocks the small plate 51, pivoted in the bracket 52 in the adjacent frame end, and causes a pin 53 in the bracket to swing the rack 40 into mesh with a gear 41. To enable the pins 53 to do this, each pin rides in a slot 54 in the back of the rack 40; and, to keep the pin in the slot, the 45 rack is prevented from falling forwardly by an ear 55^a at the front of the adjacent end-plate. When the racks 40 mesh with the gears 41, as shown in Fig. 5, the advance of the platen lifts the channel-bar 38, thus enabling a card to be inserted therein, and then, by rotating the platen, the channel-bar 50 may be set at any desired height for typing upon the card.

In order to prevent both of the handles 60 21 and 43 from being effective at the same time, there may be provided a device which normally holds the finger-piece 21 against actuation, but which is adapted to be held ineffective so long as the finger-piece 43 is 65 in its normal position. This device is herein

illustrated as a hook, comprising a lip 55, which is adapted to overlie a lip 56, projecting from the rock-arm 25. The hook, comprising the lip 55, is pivoted at 57 upon the end-plate 15, and a spring 58 normally tends to hold the lip 55 effective, by drawing 70 upon a link 59, pivoted at 60 upon the hook.

In order to hold the lip 55 normally clear of the lip 56, the link 59 is adapted to be drawn forward by the adjacent rock-arm 49, 75 which it engages by a hooked end 60^a. The connections are such that when the shaft 48 is rocked forward, it tensions the spring 58 by drawing on the link 59, through the rock-arm 49; but when the shaft 48 is rotated 80 rearwardly, the link 59 is released, thus permitting the lip 55 to become effective to lock the rock-arm 25. In order to enable the lip 55 to have a small throw, the hooked end 60^a 85 may be entirely disconnected from the rock-arm 49 early in the throw of the latter.

In order to hold the card-holding frame against accidental displacement, the shaft 48 is provided with lugs 61, which normally overlie the ends of the channel-bar 38, thus 90 locking it down. The rearward rotation of the shaft 48 carries the lugs 61 clear of the channel-bar 38, thus allowing the card-holder to rise with the advancing platen.

In order to detain the platen in its position to permit the insertion of a thick pack of work-sheets and carbons, the finger-piece extension 23 may be provided with a depression 62, terminating in a hook 63, so that, when swung forward, the finger-piece 100 is held in its swung position by the pin 34, which rests in the depression 62, and holds the lug 24 in locking position.

Variations may be resorted to within the scope of the invention, and portions of the 105 improvements may be used without others.

Having thus described my invention, I claim:

1. In a front-strike typewriting machine, the combination with a revoluble platen and 110 a platen frame having ends, of a device for withdrawing said platen rearwardly in said frame, a card-holding device at the front of the platen and normally disconnected therefrom, a finger-piece for connecting the card-holding device to the platen, and means for locking the withdrawing device by making the finger-piece effective.

2. In a front-strike typewriting machine, the combination with a revoluble platen and 120 a platen frame having ends, of links adapted to move the platen in said ends, a rock-shaft, rock arms pivoted to said links, a card-holding device, and a hook connected to said card-holding device adapted to catch one of 125 said rock arms to lock the platen.

3. In a front-strike typewriting machine, the combination with a revoluble platen and a platen frame having ends, of a handle for withdrawing said platen rearwardly in said 130

frame, a card-holding device adapted to feed a card in front of the platen, a finger-piece for making said card-holding device effective, and an interlock between said handle 5 and finger-piece such that when either is actuated the other is inoperable.

4. In a front-strike typewriting machine, the combination with a revolute platen and a platen frame having ends, of a rock-shaft 10 adapted to shift the platen relatively to said ends, a second rock-shaft, a card-holding device normally held ineffective by said second shaft, a finger-piece for each rock-shaft for making it effective, a floating link between 15 said shafts, and a pair of hooks selectively moved to effective position by said link.

5. In a front-strike typewriting machine, the combination with a revolute platen and a platen frame having ends, of a card-holding 20 device for supporting a card in front of the platen, a second device for moving the platen away from the printing point, and connections whereby the second device is inoperable when the card-holding device is 25 effective.

6. In a front-strike typewriting machine, the combination with a revolute platen and a platen frame having ends, of a card-holding device adapted to be connected to the 30 platen to carry a card in front of the platen to advance therewith, a second device for moving the platen away from the printing point, a finger-piece for each device for operating it, and an interlock between said devices to hold either inoperable when the 35 other is operated.

7. In a front-strike typewriting machine, the combination with a revolute platen and

a platen frame having ends, of a card-holding device normally disconnected from the 40 platen, a rock-shaft adjacent said device and adapted to connect it to the platen, a second device adapted to move the platen away from the printing point, a lock for said second device, a floating link, a connection 45 on said shaft adapted to draw on said link to normally hold said lock ineffective, and a finger-piece for operating said rock-shaft.

8. In a front-strike typewriting machine, the combination with a revolute platen and 50 a platen frame having ends, of a card-holding device adapted to hold a card at the front of the platen, means for moving the platen away from the printing point, a lock normally holding said device out of the 55 way, a finger-piece for releasing said device to enable it to support a card in writing position, and connections for automatically locking said means by actuation of said finger-piece.

9. In a front-strike typewriting machine, the combination with a revolute platen and a platen frame having ends, of a device for withdrawing the platen rearwardly in openings in said ends, a card-holder adapted to 60 hold a card at the front of the platen, racks connected to said holder adapted to mesh with gears upon the platen, means for swinging said racks into and out of mesh, and means for locking said device by operating 65 said means to swing the racks into mesh.
